ATTORNEY

UNITED STATES PATENT OFFICE.

FRANK F. WOOD, OF BROOKLYN, NEW YORK.

FASTENING DEVICE.

SPECIFICATION forming part of Letters Patent No. 687,550, dated November 26, 1901.

Application filed April 26, 1901. Serial No. 57,367. (No model.)

To all whom it may concern:

Be it known that I, FRANK F. WOOD, a citizen of the United States, residing in the borough of Brooklyn, in the county of Kings and city and State of New York, have invented certain new and useful Improvements in Fastening Devices, of which the following is a specification.

This invention relates to means for securing a band of wire or the like about a box or packing-case, and especially to those forms where a wire is passed about a box or packing-case and secured at its ends to form a seal.

The object of the invention is to provide a device, which for convenience may be called a "nail," for securing or fastening both ends of the wire, this nail being provided with two or more keepers for the wire, and said keepers being situated adjacent to and at different distances from the head end of the nail for reasons that will be hereinafter set forth.

In the accompanying drawings, which serve to illustrate the invention, Figure 1 is a perspective view of the preferred form of the nail or wire-fastener, the view being approximately of full size for ordinary use. Fig. 2 is a perspective view, on a small scale, of a wooden box or packing-case, illustrating one application of the invention. Figs. 3, 4, 5, 30 and 6 are illustrative sectional views showing the different successive stages in driving in the nail or wire-fastener. Figs. 7, 8, 9, 10, 11, 12, and 13 are views illustrating different arrangements of the keepers in the nail and different ways of threading the wire through the holes or keepers in the nail.

The nail A, Fig. 1, will be, by preference, cut or punched from metal plate, as iron or homogeneous steel, of tapered form and will have in its head end a, where it is broadest, three holes a' a² a³ to form keepers for the binding-wire b about the box B. (Seen in Fig. 2.)

Figs. 3 to 6 illustrate how the nail is used. Fig. 3 shows the nail driven in until the hole a' is just above the surface of the wood and the end of the wire b passed through it. A blow of the hammer sinks the nail in until the wire in the hole is bound by the wood, as seen in Fig. 4. The wire b is now passed and drawn about the box and its other end passed through

the hole a², and a blow of the hammer drives the nail still farther in until this end of the wire is also bound by the wood. This will effect a secure fastening of the wire at both ends; 55 but I prefer to go still farther to effect a secure seal. The surplus of the first end of the wire secured is passed through the hole a' and then back through the hole a³, as seen in Fig. 4, and after the fastening of the last end of 60 the wire, as seen in Fig. 5, the surplus ends of the wire are twisted together and the nail driven in flush, as seen in Fig. 6.

Figs. 8 and 9 illustrate another way of twisting together the ends of the wire. This will 65 require no explanation.

Figs. 7, 10, 11, and 12 merely show different ways of shaping or forming the wire keepers or retainers. In Fig. 7, for example, the two keepers or holes a' and a² are connected by 70 a slot. In Fig. 10 the keeper or hole a³ is omitted, and the keepers a' and a² are open at the edges of the nail, so that the wire need not be threaded through them. In Fig. 11 the keepers a' and a² are substantially the 75 same as in Fig. 10, but the hole a³ is retained. In Fig. 12 the keeper a³ is open, so that the wire need not be threaded through it. Fig. 13 shows the keepers formed in a nail having a body that is nearly square in cross-section. 80 These several views are employed merely to illustrate the various ways in which the essential features of my invention may be embodied.

I may say that the only object in putting 85 the keepers out of line or "staggering" them is that it puts one end of the wire conveniently abreast of the other instead of directly over it. In Fig. 13, where the nail is narrow, the keepers are alined.

The size and special form of the nail is not 90 material to my invention, nor is the particular material from which they are made. They might be barbed in a known way, if desired. By "wire" is herein meant any narrow band-like flexible material capable of being used with my fastener.

Having thus described my invention, I claim—

1. A straight nail or wire-fastener having a 100 point, a head end to receive the blow in driving, and a plurality of keepers all adjacent

to said head end, but at different distances therefrom, said keepers being formed in the body of the nail to receive the wire and clinch it to the wood in which the nail is driven.

5. 2. A nail or wire-fastener having a point, a head end to receive the blow in driving, a round hole at a little distance from said head end to form a keeper for the wire, and one or more round holes near said head end but 10 at a greater distance therefrom than the first-named hole, substantially as and for the purpose set forth.

3. A nail or wire-fastener having in it two or more keepers for the wire adjacent to its

head end, said keepers being staggered and 15 situated at different distances from said end.

4. A nail or wire-fastener having a point, a head end to receive the blow in driving, and three keepers for the wire situated at different distances from but adjacent to its head 20 end.

In witness whereof I have hereunto signed my name, this 22d day of April, 1901, in the presence of two subscribing witnesses.

FRANK F. WOOD.
